UNITED STATES PATENT OFFICE

GEORGE B. COE, OF WATERBURY, CONNECTICUT, ASSIGNOR, BY MESNE ASSIGNMENTS, TO TUBE REDUCING CORPORATION, OF WILMINGTON, DELAWARE, A CORPORATION OF DELAWARE

APPARATUS FOR REDUCING METAL STOCK

Application filed July 2, 1930. Serial No. 465,364.

This invention relates to apparatus for reducing metal stock and in particular to apparatus for reducing the cross-sectional area of tubular stock by working it in successive increments toward the starting end of the stock.

The object of the invention is to provide improvements in this art. The nature and objects of the invention may best be understood from the disclosure of a selected embodiment of the invention given by way of illustration. This will now be described with reference to the accompanying drawings in which:

15 Fig. 1 is a top plan view of apparatus embodying the present invention;

Fig. 2 is a side elevation;

Fig. 3 is a central vertical section on the line 3—3 of Fig. 1;

20 Fig. 4 is a transverse vertical section on the line 4—4 of Fig. 1;

Fig. 5 is a transverse vertical section on the line 5—5 of Fig. 1;

Fig. 6 is a transverse vertical section on 25 the line 6—6 of Fig. 1;

Fig. 7 is a horizontal section on the line 7—7 of Fig. 2; and

Fig. 8 is a vertical section of a detail along the line 8—8 of Fig. 7.

30 The apparatus is of the type which reduces stock in successive relatively short increments worked down toward the starting end of the stock. The tools for working upon the stock may be referred to as swages because they act repeatedly and successively to reduce the stock. There are several known types of such tools or swages, all of which are substantially equivalent to gapped eccentric rolls.

40 The present apparatus employs (Fig. 7) oscillating rockers 10 journaled in a reciprocating frame or saddle 11 slidably mounted on a base frame 12. The saddle is reciprocated by a connecting rod 13 actuated

45 by a crank shaft 14. The shaft is driven by any suitable motive means. It is counter balanced by a weight 15. The rockers are constrained to have substantially a rolling movement along their adjacent edges, that is, their

50 working faces are held by suitable means (not

shown) to rock or roll relative to an axial plane or line.

In the case of tubular stock—and it may here be stated that tubular stock is the major consideration at the present time and that the description will be directed almost exclusively thereto—a mandrel 16 is provided for supporting the tubular stock 17. This mandrel is preferably mounted in a tail stock which holds the mandrel substantially against longitudinal movement, rotates it the required amount to change the posture of the stock, and permits tubes to be fed into the machine over the rear end of the mandrel so as to travel to the reducing devices in end-to-end relationship continuously. This tail stock mechanism is not illustrated herein but a portion of the drive mechanism for the mandrel turning device is illustrated.

Referring to Fig. 1, the mandrel turning drive mechanism comprises a gear 20 on the main crank shaft 14, driving a gear 21 on a stub shaft 22, the gear 21 in turn (Fig. 6) driving a gear 23 on a lay shaft 24. The lay shaft (Fig. 6) is mounted at one end in the base frame of the machine and at its outer end in a bearing in a depending bracket 25.

The lay shaft 24 also (Fig. 7) carries an eccentric or elliptical gear 26 driving a similar gear 27 on a transverse shaft 28. This shaft 28 at its inner end carries a bevel gear 29 meshing with a bevel gear 30 on a Geneva arm shaft 31. The shaft 31 (Fig. 3) carries a Geneva arm 32 with a roller 33 and also a holding cam 34 for engaging notches in the Geneva disc 35 between turning movements.

The Geneva disc 35 is mounted on a tubular shaft 36 and is provided with slots 37 cooperating with the roller 33 of the arm 32 and with arcuate notches 38 cooperating with the holding cam 34. There are enough slots on the Geneva disc to provide smooth action of the parts. Herein six slots are used.

The shaft 36 is made tubular because it is located on the axis of travel of the stock and must permit the stock to pass therethrough. The bore of the shaft is made large enough to pass the largest stock the machine will handle.

At its front end the tubular shaft 36 carries

a gear 39 meshing with a gear 40 rotatably mounted upon a stock turning shaft 41. Co-operating with the gear 40 is a clutch sleeve 42 slidably keyed on the shaft 41. The sleeve 42 is retained by a collar 43. The shaft 41 extends to the tail stock of the machine to drive the mandrel turning mechanism which has been alluded to.

Referring to Fig. 1, the clutch sleeve 42 is provided with an annular groove 44 in which operates the bifurcated end of a clutch shift arm 45 fast to a vertical shaft 46. The shaft 46 is mounted in a bearing bracket 47. At its upper end it is provided with a rigid arm 48 connected at its outer end by a pivot pin 49 to an adjustable actuating link 50. The link is attached to a shift handle 51 journaled upon a stud shaft 52 borne by the upstanding bracket 53.

The turning mechanism will operate and alternately rest because of the Geneva gear. It has only a short time to operate because it must operate at the end of the rocker stroke between the time the rockers release the stock when approaching the end of their stroke and the time they again grip the stock on their return stroke. The eccentric or elliptical gears provide this quick motion or rather accentuate the speed of the motion which is already provided by the Geneva gear.

Tension rods 54 extend from the front end of the machine to the tail stock to tie the parts rigidly together. Specifically, the tie rods are attached at one end to the tail stock which holds the mandrel substantially fixed longitudinally and the frame 55 which carries the mechanism for sliding the stock along the mandrel.

The feeding mechanism is of the type which engages the stock intermittently to feed it to the reducing device. Inasmuch as it is desired that the stock move forward without interruption and without dismantling the machine, the feeding mechanism is preferably of the type which is capable of feeding stock continuously one length after the other to the reducing device.

Herein (Fig. 7) the feeding mechanism comprises gripper jaws 60 for directly engaging the outer longitudinal surface of the stock. These jaws (see also Fig. 5) are mounted in tapered guideways 61 formed in a reciprocating feed frame 62 slidable along guide supports 63. The frame is retained upon the guide supports 63 by plates 64 held by cap bolts 65. The guide supports 63 are formed on the fixed feed mechanism supporting frame 55 previously mentioned, the same being secured to the base frame 12 by cap bolts 66.

The jaws 60 are interiorly roughened to engage and hold the stock. They are urged to move forward by coil springs 67 engaging their rear ends. The springs at one end are seated in sockets 68 formed in the ends of

the jaws and at their other ends engage annular steps formed on adjusting screws 69. The adjusting screws are threaded through an extension 70 formed on the reciprocable feed frame 62. The extension 70 has an aperture therethrough between the adjusting screws 69 to accommodate the stock.

Means are herein provided for causing the jaws to grip the stock and subsequently causing the feed frame to move forward with the jaws to feed the stock. It is preferable that the gripper actuating mechanism be somewhat resilient and act more or less independently of the forward-feeding mechanism, the latter being substantially positive in its operation.

The clamping and feeding operations are herein both accomplished through the same actuating device. Referring to Figs. 5 and 7 it is found that bell-crank feed-and-clamp levers 72 are mounted upon journals 73 secured in the reciprocating frame 62. Bushings 74 are disposed between the journals 73 and the levers 72. The journals may be retained in the frame 62 by nuts 75. The entire assembly of movable parts may be retained within the frame 62 by a cover plate 76 held by cap bolts 77. In Fig. 7 the rear arms of levers 72 are shown in dot and dash lines for the sake of making the sectional view more understandable, though of course it will be understood that these parts are actually above the plane on which the section is taken.

From Fig. 7 it appears that the rear arms of the levers 72 are formed with retaining sockets forming a connection with the rounded ends of push links 78. As shown in Fig. 1 the ends of the links 78 are retained within the sockets in the levers 72 by plates 79 and bolts 80. The other ends of the links 78 are similarly retained by plates 81 and bolts 82 within sockets formed in the adjacent ends of rock levers 83. The rock levers 83 are pivoted upon journals 84 secured in the fixed feed frame 55. The upper ends of the journals 84 are held in spaced relation by a cross-bar 85. The cross-bar and the rock arms are retained upon the journals 84 by nuts 86.

The outer ends of the rock levers 83 are provided with sockets to retain the round ends of plunger push links 87, the parts being held together by plates 88 and bolts 89 as before. The front ends of the links 87 are rounded and fit within sockets formed in the rear ends of main plungers 90. The connection is maintained as before by plates 91 and bolts 92.

The main plungers 90 are slidable within barrels 93 attached to the fixed feed frame 55 by cap bolts 94. At the front ends the plungers 90 are provided with caps 95 screwed thereon. These caps have a central bore and are hardened on the annular surface on the end which is exposed.

Within bores 96 formed in the main plung-

ers 90 are disposed secondary or clamping plungers 97. These plungers 97 are guided at their rear ends in counter-bores 98 and at their front ends are guided in the bores 5 formed in the caps 95. Springs 99 encircling plungers 97 and acting against heads 100 formed thereon constantly tend to move the clamp plungers 97 out of the main plungers 90. The heads 100 in cooperation with the 10 caps 95 retain the plungers 97 within the main plungers 90. The plungers 97 extend through the caps 95 and the extensions 101 which are exposed are threaded to receive nuts 102. The nuts 102 secure between them 15 the cross-bar 103 which is slipped loosely upon the extensions 101.

The outer ends of the extensions 101 are hardened to withstand the constant striking action of associated parts. These ends are 20 struck by portions of the saddle 11 when it approaches the rear end of its stroke. This acts first to push the clamp plungers 97 rearwardly against spring 99 to push the main plungers rearwardly and through the related 25 parts to cause the jaws 60 to close upon the stock. The jaws close by rearward movement and as is obvious the clamping action is resilient because the motion is transmitted through the springs 99. After the clamping 30 action has been completed the rear nuts 102 bring up against the hardened annular flange of the cap 95 and force the main plunger further toward the rear, which causes the levers 72 and their journals to move forward 35 bodily, carrying with them the feed frame, feed jaws and the stock. This secondary action is accomplished without the interposition of springs and is therefore positive in its nature.

40 Means are provided for assisting the turning movement of the bell-crank clamp-and-feed levers 72 to cause the jaws to clamp the stock. The cross-bar 103 comprises a part of these means. As shown in Fig. 1 the bar 103 at its central portion is provided with a push pin 105 upon which is loosely mounted a long coil spring 106. At the front end the spring engages a collar 107 formed on the push pin 105 and at its rear end engages a 45 collar 108 attached by connecting pins 109 to toggle arms 110 mounted on the bolts 80. The push rod and spring are guided by spaced apertured brackets 112 held by cap bolts 113. The rear end of the push rod 105 has a head 114 which prevents the parts 50 moving too far forward under the action of the spring.

The spring is compressed when the feeding mechanism acts by the bar 103 being moved rearward. This moves the collar 108 rearward also tending to straighten the toggle links and spread the rear arms of the bell-crank levers 72 apart. When the action 55 of the saddle on the plungers has ceased

the spring expands again causing the bar 103 to be returned to its forward position.

Means are provided for returning the reciprocating feed frame 62 to its rearward position. As shown in Fig. 8 this is accomplished by return plungers 116 mounted within bores 117 formed on each side of the frame 62. The plungers 116 are provided with stems 118 extending outward through openings formed in small counterbores of the bores 117. Springs 119 disposed in the bores 117 and acting between the bases of the bores and the rear ends of the plungers 116 tend to force the plungers out of their bores. The 70 plungers at their front ends engage fixed upward abutments 120. The plungers are retained within the bores by nuts 121 threaded on the stems 118. The nuts may be tightened in different positions to adjust the 75 length of movement of the plungers 116. It will be seen that this mechanism constantly urges the feed frame 62 rearwardly.

The feed frame 62 is limited in its rearward movement by stop pins 122 screwed into the rear end of the frame. The ends of the 80 stop pins 122 are hardened and, as shown in Fig. 7, are adapted to engage abutments 123 when the frame moves rearwardly.

Means are provided for holding the feed frame for a time after it has been moved forward. When so held, the jaws will be kept firmly clamped upon the stock due to their inclined guide mounting and to their being pressed rearwardly by the bell crank levers. 90 It has already been noted how the saddle strikes first the auxiliary plungers which act through the springs to swing the bell crank levers about their pivots and clamp the jaws. The nuts 102 are so adjusted that the spring 95 action is not completed before the clamping occurs. Adjustment of the nuts 102 also regulates the amount of stock feed. There is a short period after clamping and before feeding in which the movement of the saddle is 100 taken up in the interposed springs. Thereafter the feeding takes place through the action of the saddle upon the main plungers which cause the bell crank levers to move forward bodily carrying their journals, the feed frame in which the journals are mounted, the jaws and the stock. The matter of holding the stock forward after feeding assists the action of the rockers upon the stock, especially when starting to work on a new 110 length of stock.

The holding means herein illustrated comprise (Figs. 1 and 3) hooks 125 secured to the feed frame by cap bolts 126. The hooks are engaged by latch plungers 127 which are slidably mounted in guides 128 formed on a 125 cross member 129. One side of the openings for the plungers comprises removable side walls 130 held by cap bolts 131. The cross member 129 is retained by cap bolts 132 passing through slotted holes 133 in the member 130.

which by this mounting is permitted longitudinal sliding movement for adjusting its position.

The cross member 129 is adjusted by a set 5 screw 134 provided with a head 134a held within a recess of member 129 by a retaining plate 135. The set screw is threaded through an upstanding bracket 136 (see also Fig. 4) held to a fixed part by cap bolts 137.

10 Normally the latch plungers 127 are urged upward into engaging position (Fig. 4) by coil springs 127a.

Means are provided for actuating the latch plungers. The guide members 128 for the 15 plungers 127 are provided with vertical slots in the side thereof for movement of stud pins 138 secured to the plungers. Links 139 are pivoted at one end to the pins 138 and at the other end to pivot pins 140 to connect them 20 to arms 141 fast on a latch release shaft 142.

At its outer end the shaft 142 (Fig. 2) is provided with an arm 143 pivoted by pin 144 to a link 145. The link 145 at its other end is pivoted by pin 146 to a cam lever 147 25 mounted on a journal 148. The journal is carried by a bracket 149 secured to a fixed part by cap bolts 150. At its outer end the cam lever 147 carries a cam follower roller 151 cooperating with a cam 152 secured to 30 the main crank shaft 14.

The links 145 provide for moving the latch plungers in any position of the cross member on which they are carried. The operation of the holding mechanism will be obvious. Usually turning of the stock occurs 35 when the saddle is at the front end of its stroke so the cam 152 is set to release the stock from the feeding mechanism before the turning action is begun.

40 In operation the saddle 11 as it approaches the rear end of its stroke comes against the ends of the clamp plungers 97. This moves the plungers rearwardly and they first act through the interposed plunger springs 99

45 and the described linkage to move the jaws 60 rearwardly in their inclined guides against the light springs 68 to clamp the stock. Further rearward movement of the plungers 97 brings them solidly against the end of the 50 barrels 93 to eliminate the action of the springs 99 and through the same linkage as that by which clamping was effected to move the feed frame 62 forward. This is possible because the pivots 73 for the jaw clamping

55 levers 72 are borne by the frame. In this movement the return spring 106 is compressed between the bar 103 and the toggle arms 110.

When the feed frame is moved forward to 60 feed the stock it is caught by the latches 127 and is held forward, and although the saddle 11 withdraws on the return movement thereof from the plungers the jaws will be held in clamped position because when the 65 feed frame is held forward the levers 33 of

the clamp and feed linkage will be held in the same position as they occupied when operated by the plungers 90. This will hold the stock fast until the rockers have had an opportunity to begin reducing it sufficiently 70 so that when the stock is released it will not move.

After a short time the cam 152 on the shaft 14 acts upon the cam roller 151 on the lever 147 and through the linkage described releases the latches 127. The spring 106 then expands to force the cross bar 103 and associated plungers 97 forward and by mutual interaction to force the toggle levers 110 and associated parts rearwardly to release the 75 jaws and move the feed frame rearwardly.

One embodiment of the invention has been described in detail for purposes of illustration. It is to be understood, however, that modifications are permitted within the scope 80 of the subjoined claims.

What I claim is:—

1. In apparatus for reducing stock progressively in relatively short increments of length, comprising in combination, gripping jaws, rearwardly convergent guides along which said jaws slide, a feed frame in which said jaws are mounted, said frame moving in an opposite direction to feed from the direction in which said jaws slide to clamp the stock, a bell crank lever journaled on said feed frame, a main plunger connected by linkage to said lever, an auxiliary plunger mounted in said main plunger and a spring tending to cause relative movement therebetween, means striking the end of said auxiliary plunger to cause said lever first to clamp said jaws through resilient spring action and subsequently to cause said feed frame to move to feed the stock, and means to restore said 90 parts to initial positions.

2. In apparatus for reducing stock progressively in relatively short increments of length comprising in combination, gripping jaws, rearwardly convergent guides along which said jaws slide, a feed frame in which said jaws are mounted, a bell crank lever journaled in said frame, one end of said lever engaging the end of a jaw to move it endwise to clamp the stock when said lever is rotated about its axis, and said lever moving forward bodily with its pivot and the feed frame to feed the stock, resilient means for clamping and positive means for feeding, both means acting through said lever. 100

3. In apparatus for reducing stock progressively in relatively short increments of length, comprising in combination, clamping jaws mounted in a feed frame, clamp-members acting to clamp said jaws and subsequently to slide said frame, and means for actuating said members including interposed resilient devices, the resilient devices not being sufficiently strong to produce feeding action but acting throughout the time of 110 120 125 130 135 140 145 150 155 160 165 170 175 180

clamping and for a short period thereafter.

4. In apparatus for reducing stock in successive relatively short increments of length, comprising in combination, a slidable feed frame, feed jaws slidably mounted therein, clamp-feed levers mounted on said frame for clamping said jaws and subsequently sliding said frame, and coordinating plungers acted upon successively by a striking device for 10 operating said levers.

5. Apparatus of the character described comprising in combination, a fixed frame, a feed frame slidably mounted therein, jaws slidably mounted in said frame, clamp feed levers journaled on the feed frame, a set of 15 two plungers successively acted upon by a striker and both movable in one direction to rotate said levers and translate them in the direction opposite to said plunger movement, and means for assisting the rotation of said levers for clamping, said means comprising 20 a cross bar connected to said plungers, a spring plunger connected at one end to said cross bar, a spring thereon, a collar at the 25 other end of the spring through which said spring plunger is slidably, members connected to said collar and said levers to spread their ends apart and a head on said spring plunger to limit its movement in the reverse 30 direction.

6. Apparatus of the character described comprising in combination a feed frame slideable forward to feed, rotatable means mounted thereon, rock levers and rearwardly moving 35 plungers to operate said levers to rotate them and subsequently slide them together with the feed frame, means acting on said levers to assist in rotating them and thereafter tending to restore the levers and plungers to original position, and means for restoring said feed frame to original position.

7. Apparatus of the character described comprising in combination, a feed frame slideable forward to feed, rotatable means mounted 45 thereon, rock levers and rearwardly moving plungers to operate said levers to rotate them and subsequently slide them together with the feed frame, and means acting mutually on said levers and plungers to restore 50 them to original position.

8. Apparatus of the character described comprising in combination, a slidable feed frame, feed jaws therein which are kept clamped when said frame is held in a forward 55 position, latches to hold said frame forward, a member supporting said latches, and means for adjusting the position of said member.

9. Apparatus of the character described comprising in combination, a slidable feed frame, a latch to hold said frame in a position to which it has been moved, means for adjusting the axial location of said latch, and latch actuating means operative thereon in 60 all adjusted locations thereof.

10. Apparatus of the character described comprising in combination, a slidable feed frame, a latch to hold said frame in a position to which it has been moved, means for adjusting the axial location of said latch, and latch actuating means operative thereon in 70 all adjusted locations thereof, said means comprising a rotatable cam and linkages for transmitting motion of the cam to said latch.

11. Apparatus of the character described comprising in combination, a slidable feed frame, means for moving said frame in one direction and means for returning said frame, said returning means comprising a plunger mounted in said frame, a spring urging said 80 plunger therefrom, an abutment against which the exposed end of said plunger contacts, a stem on said plunger extending through said frame and means adjustable on said stem for adjusting the length of movement of said plunger.

12. Apparatus as set forth in claim 11 in which an abutment and stop is provided to limit the return movement of said feed frame.

13. In apparatus for reducing stock comprising in combination, intermittently operating reducing devices, means for feeding the stock relative to said reducing devices, a hollow shaft forming part of a drive train for operating a part of said apparatus, the opening through said shaft being continuous and of a size to pass said stock, and means to rotate said shaft.

14. Apparatus for reducing stock in successive relatively short increments of length, comprising in combination a reciprocable frame for operating stock reducing devices, devices for intermittently gripping the stock in timed relation with the operation of said frame, and means including a striker and a resiliently pressed plunger for actuating said stock gripping devices to grip and feed the stock, the actuating means for said gripping devices being located conjointly on said reciprocating frame and on the frame carrying 100 said gripping devices.

15. Apparatus for reducing stock in successive relatively short increments of length, comprising in combination, a reciprocable frame for operating stock reducing devices, devices for intermittently gripping the stock in timed relation with the operation of said frame, and means including a striker and a resiliently pressed plunger for actuating said stock gripping devices to grip and feed the 110 stock.

In testimony whereof, I have signed my name to this specification this 27th day of June, 1930.

GEORGE B. COE. 125
